ELECTRIC HEATING UNIT

Charles B. Curtiss, Bay City, Mich., assignor to
Valley Welding & Boiler Co., Bay City, Mich.

Application April 17, 1947, Serial No. 742,133

2 Claims. (Cl. 201—64)

1

The present invention relates to electric heating units and more particularly to a heating unit for use in garbage disposal apparatus.

The primary object of the invention resides in the provision of an electric heater for garbage disposal units and the like, which, while protecting the heating element from corrosion of surrounding materials, will at the same time provide electrical insulation and good heat radiation for drying, heating, or igniting surrounding materials.

Another object of the invention resides in the provision of an electric heater unit for garbage disposal units and the like, which will produce drying temperatures over a relatively long time period before reaching a maximum temperature, so that the refuse in the garbage disposal unit will be considerably dried before final ignition takes place, then obnoxious odors and smoke are eliminated and other deleterious effects are reduced.

A further object of the invention is to provide a heating unit for garbage disposal units and the like in which the electric heating element is cast in or embedded in a sheath of alloy metal of sufficient sectional dimensions to slow the heating period to a gradual heating cycle of from 30 to 60 minutes, and extend the drying period during heating and cooling when the electric power is supplied intermittently.

Still a further object of the invention is to provide a heating element of the above-mentioned type in which the heating unit is cast in an alloy metal, so that the radiating surface of the sheath will be considerably increased so that the temperature of the heating unit will be only slightly greater than the temperature of the sheath, thus increasing the life of the heating unit.

Another object of the invention is to provide a heating unit for garbage disposal units in which the proximity of the sheath of the heating element to the surrounding cast alloy sheath, and the heat conductivity of the cast alloy sheath causes heat to be taken away from the unit at a faster rate than can be accomplished without the cast alloy sheath.

Another object of the invention is to provide an electric heating unit having a heating element cast in a sheath of cast alloy of sufficient sectional dimensions to increase the heat emission rate of the sheath with the resultant lowering of temperature of the sheath as well as the heating element.

Another object of the invention is to provide a heating unit of the above-mentioned type which

2

is provided with an enlarged housing portion for receiving so-called "cold" ends of the electric heating element so that a considerable space between the cold ends of the heating element and the housing portion will be provided to form a junction box structure and facilitate connection of the ends of the heating element with lead-in conductors.

Another object of the invention resides in the method of casting the electric heating element in a sheath of cast alloy in such a manner as to prevent the heat of the poured metal from melting and shorting the electric heating element and also from breaking down the insulation in the area adjacent the cold ends of the electric heating element.

Another object resides in the method of designing the cast alloy sheath for the electric heating element in such a manner that the heat of the metal melted for pouring and the latent heat of fusion during freezing will be absorbed by the core for the enlarged housing portion as well as the mold therefor.

Another object resides in the method of casting in a bushing where the unit may be machined, thus getting machinability and also added protection for the cold ends of the heating element by absorbing heat from the poured metal.

Other objects and advantages of the invention will become apparent during the course of the following description of the drawings wherein:

Figure 1 is a side elevational view of a garbage disposal unit showing a side wall portion broken away to illustrate the location of the heating unit and the general arrangement thereof.

Figure 2 is a vertical cross sectional view of the heating unit showing in detail the enlarged housing portion for receiving the ends of the electrical heating element and thus facilitate connection of said ends with lead-in conductors.

Figure 3 is a top elevational view of the heating unit, showing portions thereof in section to illustrate the general structure as well as various details, and;

Figure 4 is a side elevational view of the heating unit, showing the circular contour of the major portion thereof and the integral housing portion projecting axially and radially therefrom.

In the drawings, attention is first directed to Figure 1 wherein there is shown an adaptation of the invention in the form of a garbage disposal unit, including an insulated casing 5 provided with a receiver chamber 6 disposed above an ash drawer 7. Grate supports 8 are disposed between the receiver chamber and the removable drawer 7.

and a movable grate 9 is disposed above said grate supports and is operable by a shaker bar 10 having a projection 11 for engaging within an opening in the movable grate 9 so that the to-and-fro movement imparted to the bar 10 will reciprocate the movable grate 9.

Mounted near the top of the casing 5 is a flue pipe 12 for conducting the products of combustion to the atmosphere. Also, a hinged cover 13 is secured to the open top of the casing 5 to permit the dumping of refuse and garbage into the receiver chamber 6.

The electric heating unit generally designated 15 is mounted in the receiver chamber 6 and is supported above the grate 9, so as to project upwardly into the receiver chamber 6. As shown in Figure 1, the electric heating unit is supported on the front face of the combustion chamber and is connected to the inner end of a tubular member 16, the outer end of which projects through a sleeve in the wall of the garbage disposal unit 5 and is rigidly connected thereto by means of retaining units (not shown). An outlet box 18 is affixed to the free end of the tubular support 16 for accommodating cable connections with a suitable source of electrical energy.

The electric heater unit 15 is circular in shape to provide an annulus 20, Figures 2, 3, and 4 of round section. The annulus 20 is formed of an alloy metal of proper characteristics for heat dissipation and corrosion resistance.

The type of metal used in the alloy sheath will often be too hard for easy machining, so that to facilitate threading for the connecting support a bushing insert may be cast in the alloy where it may be machined to accommodate the supporting tube or other member. This makes possible the use of the best cast alloy analysis for getting the best operating life of the heating unit.

Formed integral with the annulus 20 is a housing generally designated by the reference character 22, and said housing projects both radially and axially of the axis of the annulus as is shown clearly in Figures 2 to 4 inclusive. The housing is likewise formed of cast alloy and includes an inclined wall portion 23 terminating in a bottom wall 24 extending axially of the annulus (Fig. 2). A top wall 25 of arcuate shape extends axially for a portion of its length and terminates in an inclined wall portion converging in the direction of the lower wall 24. A curved side wall portion 26 connects the bottom and top walls 24 and 25 and provides a rounded front wall section 28 having an enlarged threaded boss 27 for receiving the threaded inner end of the supporting tube 16 (Figs. 2 and 3).

Thus, an enlarged chamber 30 is formed between the annulus 20 and the tubular support 16 to facilitate electrical connections with the electric heating element 31 which is embedded or cast in the annulus. The electric heating element comprises a resistance wire 32 surrounded by steel or heat resistant alloy sheath, the wire is insulated from the sheath by a closely packed layer of magnesium oxide, the resistance wire extending approximately 270° of a circle.

Between the ends of the resistance wire and the connections are two large low-resistance wires in the cold end sections; these are similarly insulated from the sheath and can be threaded on the ends to afford means of connection with the cable conductors extending through the tubular support 16 which are also insulated from said support by magnesium oxide or other insulating material.

It will thus be seen that the electric heater element is cast in a sheath of considerable thickness in such a manner that heat will be conducted away from the electric heater element 31 at a greater rate than would occur if the heater element 31 were spaced from the sheath.

By reason of the annular shape of the heating unit, the radiation area is greatly increased, thus insuring a greater rate of heat emission and a resultant lower temperature of the sheath and therefore of the entire unit including the heating element 31. The theoretical radiation is expressed in the Stefan-Boltzmann 4th power law of radiation by the formula:

$$Q = K \times F \times t \times \frac{(T)^4}{100} - \frac{(T_0)^4}{100}$$

where, for example, Q=B. t. u. to be radiated taken as 600 watts or 2047 B. t. u. per hour.

20 K=constant for cast alloy=.157 approx.
F=area of radiating surface, taken as 0.4 sq. ft.
t=time in hours, taken as 1 hour.
T=Absolute temp.: °F. of sheath or annulus 20.
T₀=Absolute temp.: °F. of surrounding space.

25 Then the difference between the temperature of the annulus or sheath and the ambient temperature for various temperatures can be deduced by the above formula, which in the example will be found to be as follows:

30 Ambient temperature °F. 212, 500, 1000, 1500, 2000,
Approximate annulus or sheath temperature °F. 906, 964, 1211, 1601, 2051,
35 Differential-sheath-ambient temperature °F. 694, 464, 211, 101, 51

40 Thus, it will be seen that as the ambient temperature is increased, the radiation is more than proportionately increased and hence, the heating element temperature is not equally increased.

45 All materials radiate heat at elevated temperature at a greater rate than at lower temperatures. Thus at elevated ambient temperatures, at say in the neighborhood of 1500° F., there will be only 101° F. difference between the temperature of the heating unit sheath and the surrounding temperature. This temperature difference is exactly the desired result as it eliminates failure of the heating element due to overheating, since the ambient temperature will seldom, if ever, cause unit temperatures that are excessive.

Method of molding heating unit

55 In the casting of the heating unit 15 including the annulus 20 and the housing 22, conventional foundry equipment is employed.

60 A pattern shaped identical to the heating unit 15 and housing 22 is employed for forming the mold cavities in the mold sand in the cope and drag of the mold. After the mold cavity is then formed, the electric heating element 31 is arranged in a circular manner in the annular portion of the mold and said heating unit is chaptered to assure proper location in the center of the element 15.

65 The free ends of the electric heating unit are embedded in a dry sand core placed in the housing cavity in the mold so that upon casting, the ends will be protected against high melt temperatures and will not become shorted.

70 In order to protect the "cold ends" of the heating element from failure caused by the heat of the alloy during pouring, it is necessary to design the housing so that the core itself and the 75 surrounding mold will be able to absorb the heat

of the metal of the housing without raising the temperature of the cold ends dangerously, and gating shall also further this end. Only by this design, and by this method of pouring, can the heating elements be successfully entirely encased in cast alloy.

When the electric heating unit is thus cast from a suitable alloy, the core material is removed from the casting and the casting is fettled in the usual manner. The annular boss 27 may then be threaded for receiving the tubular support 16. Before the tubular support and casting are assembled, suitable electrical connections are made with the terminals of the heating unit, and insulating material such as magnesium oxide is packed in the chamber 30 as well as the tubular support 18, and since the tubular support 16 is closed at its outer end, the electric heating unit will be completely end sealed with the electrical conductors projecting through the closed end of said tubular support.

The electric heating unit thus produced is then mounted near the front wall of the combustion chamber as shown in Figure 1 so that the annulus or sheath 20 will lie in a plane perpendicular to the tubular shaft.

It is to be understood that the form of the invention shown and disclosed is to be taken as a preferred embodiment of the invention, and that various changes in the shape, size, and arrangement of parts may be resorted to without departing from the spirit of the invention or the scope of the subjoined claims.

What I claim is:

1. An electrical heating unit, comprising a loop-shaped annular sheath formed of cast alloy, an insulated electric heating element embedded in said annular sheath, a laterally projecting, hollow housing formed integral with said annular sheath

having a cast in bushing to absorb heat while casting and to permit a threaded bore in the housing, the terminal ends of said electric heating element being received in said housing, a tubular support having one end received in said threaded bore, electrical conductors extending through said tubular support and electrically connected to the terminal ends of said heating element within said housing, and insulating material packed in said housing and tubular support, said insulating material comprising magnesium oxide.

2. A method of casting a sheath around an electric resistance heating element, comprising forming a mold cavity of the shape of the heating unit desired, mounting said electrical resistance heating element within said mold cavity forming a relatively large cavity adjacent the cold ends of the heating element mold cavity, placing a core in said last named cavity with the ends of said heating unit embedded therein and gating the mold cavity so that the molten metal will flow first into said first named mold cavity around said heating unit and then between said last named mold cavity and said core.
